UNITED STATES PATENT OFFICE.

OSCAR MEYER, OF BROOKLYN, NEW YORK, AND PAUL S. MAILLEFERT, OF NEW HAVEN, CONNECTICUT; ALICE E. MAILLEFERT, ADMINISTRATRIX OF SAID PAUL S. MAILLEFERT, DECEASED.

CLOTHESLINE CLAMP.

Application filed February 5, 1920, Serial No. 356,540. Renewed January 3, 1924.

To all whom it may concern:

Be it known that we, OSCAR MEYER and PAUL S. MAILLEFERT, citizens of the United States, residing at Brooklyn, in the county 5 of Kings and State of New York, and New Haven, in the county of New Haven and State of Connecticut, respectively, have invented certain new and useful Improvements in a Clothesline Clamp, of which the 10 following is a specification.

Our invention relates to improvements in clamps for clothes-lines and primarily aims to provide a clamp including a cam which is adapted to cooperate with an adjacent 15 abutment for clamping the rope, said cam having its opposite side weighted whereby the clamping of the rope is automatically effectuated when the tension is increased.

A further object of the invention lies in 20 the provision of a clamping device in which the clamping cam is equipped with a lever that receives the free end of the rope whereby the cam may be automatically released.

A further object of the invention aims 25 to improve and simplify the structure and operation of the clamp, so as to produce an article which is reliable and effective in use, and inexpensive to manufacture.

Other objects and advantages of the in- 30 vention will be apparent during the course of the following description.

In the accompanying drawings forming a part of this specification and in which like numerals are employed to designate 35 like parts through the same,

Figure 1 is a side elevation of a clothes-line having our clamping device applied thereto;

Figure 2 is a longitudinal section of the 40 clamp;

Figure 3 is a bottom plan view;

Figure 4 is a detail view of the cam, and

Figure 5 is a section through the cam showing the groove surface.

In the drawings, wherein for the purpose 45 of illustration we have shown a preferred embodiment of our invention, the numeral 5 designates a longitudinally slotted frame having at one end a transverse aperture 6 and at its opposite end a longitudinal aperture 7 which is slightly inclined and communicates with the slot of the frame. This clamp is adapted for use in connection with clothes-lines of the movable type which

briefly consists of two pulleys 8 which are 55 secured to spaced objects and have a rope 9 passing thereover. One end of the rope 9 is fixedly secured to the opening 6 of the frame, while the opposite end passes through the opening 7 at the opposite end. 60 The free end of the rope after passing through the opening 7 passes around the pulley 10 which is pivoted, as at 10', within the slot of the frame 5 adjacent the opening 7. The rope 9 by passing through the 65 opening 7 is retained upon the pulley 10 and will prevent displacement thereof.

A cam or eccentric 11 is pivoted, as at 12, within the slot of the frame 5 adjacent the opposite end. The peripheral edge of 70 the cam closest to the pulley 10 is provided with a groove 13 having a plurality of teeth or lugs 14 for engaging and clamping the free end of the rope 9. In order that the clamping of the cam may be automatically effectuated the opposite side thereof is equipped with a weight 15 which will tighten the clamping member as the tension of the rope is increased. Extending 75 from the lower edge of the cam and formed integral therewith is a lever 16, the free end of which is bifurcated as at 17, to receive the free end of the rope 9. The rope by passing through the end of the lever 16 will automatically disengage the cam when 80 moved in a forward direction permitting the tension of the rope to be increased or diminished as desired.

In use, one end of the clothes-line 9 is fixedly attached to the end of the frame 5 by tying the rope to the aperture 6. The rope is then extended around the pulleys 8 and is passed through the passage 7 over the pulley 10 and down between the groove 13 of the cam 11. When the desired tension of the rope has been obtained the weight 15 on the opposite side of the cam 11 will automatically force the teeth 14 into engagement with the rope 9, thus effectually clamping the same. The free end of the rope rests in the bifurcated end 17 of the lever 16 and when the rope is moved in a forward direction the cam will be oscillated so that the teeth 14 will be disengaged from the rope and the tension thereof increased or diminished. It is obvious from the foregoing that a simple and effective clamping device has been produced which is reliable 85 90 95 100 105

in its operation and may be manufactured at a minimum cost.

It is to be understood that the form of our invention herewith shown and described is to be taken as a preferred example of the same, and that certain changes in the shape, size, and arrangement of parts may be resorted to without departing from the spirit of the invention or the scope of the 10 subjoined claim:

Having thus fully described our invention, what we claim is:—

In a device of the class described, the combination with a clothes line, of a frame 15 having a longitudinal slot, a pulley journaled in the slot, said pulley receiving the clothes line end passing through an opening in the end of said frame, a substantially circular cam eccentrically pivoted in the

slot, a groove formed along the peripheral 20 edge of the cam adjacent the pulley having teeth to engage the clothes line, a weight on the opposite side of the cam to normally hold the teeth in engagement with the clothes line, and a lever extending from 25 the cam to release the pulley having a bifurcated end engaging the clothes line and holding it in close contact with said pulley and facilitating in releasing the cam from engagement with the clothes line. 30

In testimony whereof, we have affixed our signatures in the presence of two witnesses.

OSCAR MEYER.
PAUL S. MAILLEFERT.
